TRUSTEE, OF HAVERHILL, MASSACHUSETTS.

SHOE COUNTER.

Application filed May 3, 1926. Serial No. 106,266.

In the manufacture of shoes by the welt or McKay process, it has become common practice to employ counters, or heel stiffeners which have both side portions extend 5 for the greater portion of the length of the shank of the shoe, or nearly to the ball portion, instead of having them terminate at the front end of the heel, as has been customary.

If the counter is properly fitted, such a 10 construction has been found to have important advantages, as compared with former practice, as the extended sides of the counter will stiffen the shank and act to afford a more effective support for the arch of the 15 foot. Also, the extended sides will act to hold the top portions of the sides of the foot opening in a low cut shoe, so that these portions will be as effective in preventing slipping at the heel as the back of the shoe. The 20 appearance of the shoe will also be substantially improved by the use of this form of counter.

In the manufacture of shoes thus constructed, various difficulties have, however, 25 been encountered, and these difficulties have been particularly great in the manufacture of pumps or slippers having high heels, in which the front portion of the shank part of the shoe is necessarily curved, or extended 30 obliquely from the level of the heel seat, to provide for the difference in elevation between the heel seat and the tread surface at the ball portion of the shoe. These difficulties, which are present in a lesser degree 35 in low heeled shoes, are due, primarily, to the fact that shoe counters, when moulded by present day methods, do not conform to the last, when the sides are extended throughout the greater portion of the shank, 40 and the lasfer, in attempting to make one portion conform to the last is likely to throw another portion out of conformance therewith.

To explain more specifically, in molding 45 counters in any ordinary counter molding machine now in use, the inturned flange is wiped in and molded flat, and it is, so far as I am aware, impractical to mold counters in any other manner. If the flange of the 50 counter did not extend beyond the flat portion of the bottom of the last, the difficulties above referred to would not occur, but, the long sided counter to be effective, should extend for a substantial distance beyond this 55 point, as for example opposite the middle of

the oblique portion of the shank, and the sides, thus extended, would not be effective unless held in place by the flange directly connected to the bottom thereof and thru which the stitches are passed into the inner 60 sole. As ordinarily constructed, the narrowest portion of the shank is at approximately the middle of the oblique portion thereof, so that, in lasting the counter onto the inner sole, which will have been placed 65 on the last bottom, the front portions of the sides of the counter have to be drawn inward to an extent, so that they will lie closely against the sides of the last at this point. This not only necessitates the drawing in of the counter flange, at its front ends, 70 onto the oblique portion of the sole bottom, but it also necessitates the longitudinal conformance of the flange therewith, and I have ascertained, that, in pressing down the front 75 end portions of the flange to make them conform to the oblique shank portion, other portions of the counter will be forced away from the last when they should conform closely thereto. This is likely to occur at any one 80 or all of three portions, depending on the way the counter is held; viz, the heel seat portion of the flange is likely to be lifted from the last, the back portion of the counter is likely to be pushed away from the back 85 end of the last and the top edges of the sides are likely to be drawn down and thrown out from the sides of the last. If the counter is made to conform at any one of these points, it will be thrown out at one, or 90 both of the others, and it has usually been a question of choosing the lesser of two or more evils. In order that the heel may be properly attached, the flange of the counter should rest firmly on the heel of the sole, and when this is forced down, after having been 95 lifted by the lasfer in conforming the front ends of the flange to the inclined portion of the shank, the back of the counter will be pushed back, so that it will overhang the heel seat at the back and somewhat at the sides. As a result, when the shoe is finished, 100 the heel does not support the sides and back of the counter, and, when the shoe is worn, the bottom portion of the counter will usually be pushed down in a roll about the side of the heel. If the sides of the counter are also drawn away from the last at their top edges, the foot opening will be unduly widened, and the sides of the upper will not lie 110

close to the foot of the wearer and will not assist in preventing slipping at the heel. Added to this, the difficulty of the lasting operation is substantially increased when 5 long sided counters, such as have previously been produced, are employed, not only for the reasons already indicated, but for the further reason that it is difficult for the laster to draw in each end of the counter to 10 the same extent, so that the edges will be of uniform height at each side. This is due to the fact that, as the top edge of the counter extends continuously with the end of the flange, and there is no clear line of demarcation 15 between the side and the flange at this point, partly due to the fact that, at this point, the side of the last is usually at but a slight angle to the bottom, the laster has no positive guide to indicate the extent to 20 which he must draw in the tips of the sides over the bottom. In consequence he is liable to draw in one side more than the other, with the result that the top edge of the counter at its front ends, will be lower at one side than 25 at the other, so that the upper will not be supported at a uniform height at each side and there will be a tendency for the upper to become crowded down at the side which is not supported by the counter at the height 30 intended.

While an apparent method of avoiding these difficulties would be to mold the shank portion of the flange to conform to the contour of the shoe shank longitudinally, there 35 is no machinery at present available with which this could be done, and if it should, in fact, be practical to produce a machine which would mold the flanges to conform to the inclination of the shank it would be necessary 40 for the counter manufacturer to have a different set of molds for each height of heel or shape of shank used by the shoe manufacturer, and it would be also necessary for the latter to keep on hand a 45 very large stock of counters for the different heights of heels, so that the expense would be greatly increased, probably to such an extent as to be prohibitive.

The objects of my invention are to provide 50 a form of counter, which may be molded by present methods, and has side portions adapted to extend opposite the middle of the oblique portion of the shank of the shoe, and which will fit snugly to its last throughout 55 its entire inner surface, without bending the same to any substantial extent, from the form in which it was molded, so that, when the flange is drawn in and fitted to the front portion of the shank, there will be no tendency 60 to push any portion thereof away from the last, whereby all the advantages of a counter of this type may be secured without incurring the disadvantages thereof, including the increase in cost of the labor of 65 lasting counters of this type. Also to pro-

vide a counter of this type which will be so formed that the laster will be readily able to set the counter in the correct position with relation to the inner sole, so that the side portions thereof will be of uniform 70 height when the operation is finished.

I accomplish these objects in the manner hereinafter described and illustrated in the accompanying drawing in which:

Fig. 1 is a top plan view of a shoe counter embodying my invention.

Fig. 2 is a perspective view thereof, bottom side up.

Fig. 3 is a perspective view showing the counter in position on a last.

Fig. 4 is a view, partly in section and partly in perspective, of a portion of the shank part of a shoe in which the counter is incorporated.

According to my invention I provide a 85 counter *a*, which may be formed from any of the materials of which shoe counters are commonly constructed, said counter being moulded in the usual U-form to fit the heel portion of a last, indicated in dotted lines 90 in Fig. 3 and having its side portions adapted to extend along both sides of the last, beyond the heel breast, and opposite the shank portion, nearly to the ball portion, the upper edges of the sides of the counter 95 being extended in the usual curved formation and terminating at the edges of the inner sole *x*, which is also indicated in dotted outline in Fig. 3, as in position on the bottom of the last ready for the lasting operation. 100

In all shoes having a heel of substantial height, as the tread surfaces of the heel and of the ball portion of the fore part must be in the same plane to have the shoe tread properly, the shank portion, which extends from the heel seat to the ball portion, must be formed at an inclination to the tread surface of the ball portion, to provide for the difference in level, the extent of inclination 110 being varied according to the height of the heel. That is, with a comparatively low heel, the heel seat and the adjacent shank portion will be nearly horizontal and nearly all of the inclination of the shank portion will be in its front portion, as at *y* 115 in Fig. 3, while, with an extremely high heel, the heel seat and rear portion of the shank part will be formed at a considerable inclination to the tread surface at the ball, and this inclination is usually substantially increased in the front portion of the shank part, but the point where this increase in 120 inclination begins varies with the design of the shoe. Usually the shank portion immediately adjacent the heel seat is extended in the plane of the heel seat and then is extended in a curve obliquely to this plane at an increasing angle, the curvature either 125 being reversed adjacent the ball, so as to 130

blend with the tread surface at the ball, or the front shank portion being extended to meet the ball surface at an obtuse angle. That is, the front portion of the shank part 5 is always inclined to the heel seat, and usually to the shank portion adjacent the heel seat, and, to secure the advantages of the long sided counter, the sides must be extended opposite this inclined portion for a substantial distance, the extent varying according to the character or design of the shoe and usually for at least one half the length of the inclined portion. In Fig. 3 the front 10 end of the sides are shown as terminating approximately midway of the inclined shank portion y , and at approximately directly opposite points, indicating common practice. The counter is also provided with the usual inturned flange c , which is adapted to conform to the flat portion of the last bottom, and extends from the heel end to, or adjacent the point in the shank portion, indicated by dotted line z in Fig. 3, at which 15 the last bottom extends obliquely to the ball portion, that is, at the approximate transverse line at which the shank surface begins to extend at a perceptible angle to the surface of the heel seat and to the adjacent portion of the shank surface. Throughout 20 this portion the flange is of the usual, and practically uniform width. From this point, each end portion d of the flange is tapered to the adjacent sides, so that the edges of said end portions extend divergently with relation to each other, the oblique edge of each flange end-portion meeting the edge of the corresponding side at an angle, the vertex e of which is designed to be so located that when the counter is held in its 25 correct position on the last each vertex, or pointed end e , will lie directly over the side edge of the inner sole, or on the corner where the bottom surface of the inner sole meets its side edge, at approximately opposite 30 points intermediate the inclined shank portion y . It will be understood, however, that the exact extent to which the sides of the counter extend opposite the inclined shank portion will depend on conditions and will 35 be varied in practice, also, that the angle at which the edges d of the tapered flange portion meet the edges of the sides at the points e will be also varied, but it is important, in order that all the advantages of the invention 40 may be secured, that these edges meet at a well defined point or angle, which bears a certain relation to the top edges of the sides, so that, in lasting the shoe, the laster may draw in the sides of the counter until 45 these points are directly over the edge of the inner sole, as shown in Fig. 3, and then may secure the counter in this position, so that each side edge thereof will be at the same height, and the counter will also then 50 be correctly positioned on the last, or held

in the position in which it was designed to be held.

As thus constructed, when the counter is fitted to the last, in performing the lasting operation, the flange c thereof will lie flat on the portion of the sole over the flat portion of the last bottom which extend from the heel end to approximately the line z , at which point the shank is extended obliquely to the tread surface of the ball. From this point the edge of the flange, at each end, is extended obliquely on, or about the shank surface, which is usually somewhat rounded transversely, so that the flange end- 55 portions are laid upon, or bent about the shank surface somewhat spirally. In conforming the flange to the sole bottom in this manner, there will be no tendency to displace the other portions of the counter, which will be held firmly on the heel seat and against the side surface of the last at all points, so that the lasting operation may be performed with no more difficulty than if the sides of the counter terminated at the heel breast. The upper attaching stitches, 60 will pass through the tapered portions of the counter flanges nearly to the extreme front ends of the sides, as indicated in Fig. 4, and as the short portions of the flange, beyond the points where the stitches leave the flange, extend to the extreme ends of the sides, these portions of the counter will be sufficiently supported thereby. Also, in drawing in the sides of the counter, at their front ends, against the sides of the last, there 65 will be no tendency to draw the sides toward the bottom, so that there will be no tendency to cause the upper edges of the sides of the counter to spring away from the sides of the last. In consequence the 70 sides of the shoe will fit closely against the sides of the foot of the wearer and there will be no tendency of the sides of the shoe to bulge out.

By forming the end portions of the flange 75 so that they taper to the sides of the counter, the length of said sides, or the distance which they extend forwardly beneath the upper above the sole, is actually increased for the same length of blank, so that a substantial saving in stock in cutting out the counter blanks may be made, while the effectiveness of the counter in supporting the upper is in no way decreased. A firm heel seat is provided and the liability of having 80 the back portion of the counter forced away from the back side of the last, in the lasting operation, is avoided, so that the back of the shoe will not overhang, or project beyond the back of the heel when finished and the shoe will not be oversize in length.

I claim:

1. A shoe counter moulded in U-form corresponding to the heel part of a shoe having 85

- an oblique shank portion extending rearward from the ball portion, each of the side portions of the counter being formed to extend throughout a substantial portion of the 5 length of said oblique shank portion and having an inturned flange portion formed for engagement with the shoe bottom and extending continuously with its lower edges, the end portions of said flange having their 10 edges extending forwardly in divergent relation and being formed to meet the top edges of the sides of the counter at points corresponding to the edge of the shoe bottom.
2. A shoe counter moulded in U-form to 15 fit the heel part of a shoe having an oblique shank portion extending rearward from the ball portion, each of the side portions of the counter being formed to extend at opposite sides of said shank portion and to terminate 20 at their front ends opposite intermediate points in said oblique shank portion, the bottom portion of the counter having an in-turned flange for engagement with the shoe bottom, the front end portions of the flange 25 being formed to extend over said oblique shank portion and to decrease in width so that their edges will meet the corresponding top edges of the sides at the edge of the shoe bottom when in position thereon.
3. A shoe counter adapted to fit the heel 30 part of a shoe having the front portion of its shank part extending obliquely to the ball portion, and constructed to have each of its side portions extend to points intermediate 35 said shank front portion at each side thereof, with the upper edges terminating at the opposite edges of said front portion, and having an inturned flange extending continuously with the under edges of the sides and 40 arranged to engage the shoe bottom, said flange being of approximately uniform width throughout the main portion thereof corresponding to the part of the shoe in the rear of said shank front portion, and being tapered from said portion to each end, so that 45 the edges of the tapered portions extend obliquely from the main portion to the front ends of the top edges of the sides, respectively.
4. A counter for a shoe having an inner sole and having the front portion of its shank part inclined to the surface of the ball portion, said counter being moulded to conform to the heel portion of the shoe and having 50 each side portion formed to extend beyond the heel breast position to points intermediate the inclined portion of the shank part, the back and side portions thereof having an inturned flange adapted for engagement with the bottom side of the inner sole 60 and the front portions of the flange having their edges extended divergently and formed to meet the top edges of the respective side portions at the adjacent edge of the inner sole, when in lasted position. 65
5. A counter for a shoe having an inner sole and having the front portion of its shank part inclined to the surface of its ball portion, said counter being moulded to conform to the heel portion of the shoe and having each side portion formed to extend beyond the heel breast position to points intermediate the inclined portion of the shank part, and the bottom portions thereof having an inturned flange arranged to engage the 70 bottom surface of the inner sole, the front portions of the flange being formed to extend onto said inclined shank portion and to taper in width, as they extend forwardly thereon, the respective edges of the tapered 75 portions and the corresponding top edges of the side portions each being formed to meet at an angle, to provide a pointed end located to be positioned at the edge of the inner sole when the counter is in lasted position. 80
6. A counter for a shoe having an inner sole and having the front portion of its shank part inclined to the surface at the ball portion, said counter being moulded to conform to the heel portion of the shoe and having each of its side portions formed to terminate 90 at approximately opposite points intermediate said inclined shank portion, the bottom portion of the counter having an inturned flange extending throughout the length thereof for engagement with the shoe bottom, the front portions of said flange being formed to decrease in width from points approximately corresponding to the rear end of said inclined shank portion to the front end of 95 the corresponding side portion, so that the flange is without substantial width at its ends, each side portion being thereby formed with a pointed front end so arranged that, when the counter is in lasted position, said 100 pointed ends will be located directly over the corresponding side edge of the inner sole. 105
- In testimony whereof, I have signed my name to this specification.
- GEORGE E. BRITTAINE.
